UNITED STATES PATENT OFFICE.

DANIEL T. TURNER, OF NEW ALBANY, INDIANA, ASSIGNOR TO ANCHOR STOVE & RANGE CO., OF NEW ALBANY, INDIANA, A CORPORATION OF INDIANA.

DESIGN FOR A STOVE.

No. 39,653.

Specification for Design.

Patented Oct. 27, 1908.

Application filed July 31, 1908. Serial No. 446,350. Term of patent 7 years.

To all whom it may concern:

Be it known that I, DANIEL T. TURNER, a citizen of the United States, residing in the city of New Albany, in the county of Floyd and State of Indiana, have invented a new, original, and ornamental Design for Stoves, of which the following is a specification, reference being had to the accompanying drawing, forming part thereof.

The figure is a perspective view of a stove showing my design.

The drawing shows the stove practically in front elevation, the especial features of the design being the scroll and ornamental work of the legs and front panel.

I claim:

The ornamental design for a stove, as shown and described.

DANIEL T. TURNER.
